UNITED STATES PATENT OFFICE

BENNO SCHUBART, OF NUERMBERG, GERMANY

DESIGN FOR A BOX FOR BABY'S SHOES

Application filed February 16, 1931. Serial No. 38,692. Term of patent 3½ years.

To all whom it may concern:

Be it known that I, BENNO SCHUBART, a citizen of the German Republic, residing at Nuremberg, Germany, have invented a new, original, and ornamental Design for a Box Baby's Shoes, of which the following is a specification, reference being had to the accompanying drawings, forming part thereof.

Figure 1 on the top shows a baby's shoe box of my design in perspective view, the lower Figure 2 shows a development of the blank from which the design illustrated in Fig. 1 has been made.

I claim:

The ornamental design for a box for baby's shoes, as shown and described.

In witness thereof I affix my signature.

BENNO SCHUBART.
